UNITED STATES PATENT OFFICE.

HENRY JOSEPH ROUND, OF LONDON, ENGLAND, ASSIGNOR TO RADIO CORPORATION OF AMERICA, A CORPORATION OF DELAWARE.

VACUUM TUBE.

Application filed July 9, 1921, Serial No. 483,490, and in Great Britain May 29, 1914.

(GRANTED UNDER THE PROVISIONS OF THE ACT OF MARCH 3, 1921, 41 STAT. L., 1313.)

It has before been proposed to employ for the purpose of magnifying or producing continuous electrical oscillations a vacuous tube containing a heated filament, a screen or grid, and an anode, the screen being connected through an inductance to a source of current, and the anode being also connected through a second inductance shunted by a condenser to the source of current, while the two inductances are so arranged that they interact on each other.

According to this invention I omit the screen from the interior of the tube and I reduce the cross-sectional area of the tube between the filament and the anode so as to form a constriction through which the discharge passes, and I place outside the tube and around the constriction a metallic coating of wire or foil, this coating being connected as was the screen through an inductance to the source of current.

Further, I arrange at each side of the constriction the poles of an electromagnet by means of the field of which the current can be adjusted to the required value.

This arrangement is illustrated by the accompanying drawing in which Fig. 1 shows a circuit including my improved tube, and Fig. 2 shows a modification thereof. V is the tube having a filament F and anode H. The tube is reduced in the middle and round the reduced portion is arranged a coating of wire or foil S connected to a high tension generator G through an inductance R shunted by a condenser K. M¹ M² are the poles of an electromagnet.

The anode H is also connected in the ordinary way to the generator through an inductance R¹ shunted by a condenser K¹ and the circuits containing the inductances R R¹ 40 are arranged so as to interact on one another.

Having described my invention, what I claim is:

1. A vacuous tube containing a hot cathode and an anode and having a constricted 45 portion therebetween, a metallic sheet round the constricted portion, and an electromagnet adjacent thereto.

2. In a vacuum tube, in combination a container having a constricted portion, a 50 cathode and an anode respectively on opposite sides of said constricted portion, said anode having greater area than the cross section of the constricted portion and having its surface substantially parallel thereto, an electrostatic control element located in proximity to said constricted portion.

3. In a vacuum tube, in combination, a container having a constricted portion, a cathode and an anode respectively on opposite sides of said constricted portion, and an electrostatic control element outside said container and surrounding said constricted portion.

4. In a vacuum tube, a container having a relatively constricted portion, a hot electrode and an anode in said container, located respectively on opposite sides of said constricted portion, and a control electrode comprising a thin sheet of metal surrounding said constricted portion.

HENRY JOSEPH ROUND.
